UNITED STATES PATENT OFFICE

GUSTAV R. RODDY, OF MILWAUKEE, WISCONSIN, ASSIGNOR TO CHAIN BELT COMPANY,
OF MILWAUKEE, WISCONSIN, A CORPORATION OF WISCONSIN

SEWAGE-DISPOSAL APPARATUS

Application filed August 18, 1929. Serial No. 386,380.

This invention relates to sewage disposal apparatus, and has for one of its objects to provide an apparatus of this character which will be simple in construction, comparatively inexpensive to manufacture and install, and more efficient in use than those which have been heretofore proposed.

In my co-pending application, filed Aug. 16, 1929, Serial Number 386,359, entitled "Sewage disposal systems", I have described and claimed a sewage disposal apparatus whereby it is possible to construct and employ concrete settling tanks of relatively great width, as compared to those which are now common, and in which the entire floor area is free and unobstructed so that it may be subjected to the cleaning and scraping action of the sludge-removing conveyors over its entire surface. In the construction described in the said co-pending application there are no division walls or supporting columns or pillars within the tank, and in order to support the upper runs of the conveyors there are provided transversely extending beams or girders spanning the tank from one side wall to the other.

In some instances, however, as, for example, in the case of tanks of extreme width, it is desirable or necessary to introduce up-right columns or pillars for supporting the superstructure on which the upper runs of the conveyors travel, while at the same time it is also desirable to have the floor otherwise free from obstructions in the form of division walls which are extremely expensive to construct whereby its entire surface, except for these pillars, may be freed of sludge by the conveyor flights. It is one of the principal objects of the present invention to provide such a construction, as will appear more fully below.

With the above and other objects in view, which will appear as the description proceeds, the invention consists in the novel details of construction and combinations and arrangements of parts more fully hereinafter disclosed and pointed out in the appended claims.

Referring to the accompanying drawings forming a part of this specification, in which

like reference characters designate like parts in all the views,

Fig. 1 is a sectional plan view of a portion of a settling tank for a sewage disposal system and its associated mechanism as constructed in accordance with the present invention;

Fig. 2 is a longitudinal vertical sectional view of the parts shown in Fig. 1, taken approximately on the plane indicated by the line 2—2 of said figure;

Fig. 3 is a transverse vertical sectional view taken approximately on the plane indicated by the line 3—3 of Fig. 2;

Fig. 4 is an enlarged detail sectional plan view illustrating the hinged wings or end members carried by the conveyor flights and the manner in which they pass the columns or pillars;

Fig. 5 is a detail perspective view of one of the columns or pillars and the superstructure supported thereby; and

Fig. 6 is an enlarged plan view, partly in section, of one of the conveyor flights, illustrating in detail the construction of the hinged wings.

Referring more particularly to Figs. 1, 2 and 3, 10 indicates generally a settling tank for a sewage disposal system having an end wall 11, side walls 12, and bottom 13. The end wall 11 is provided with suitable ports or inlet passages 14, which may be controlled by suitable valves, not shown, and which permit sewage from the conduit 15 to enter the tank as will be readily understood.

As is usual in this class of apparatus, there is provided a plurality of endless conveyors 16, each comprising a pair of sprocket chains or belts 17, to which are secured at suitable intervals the transverse flights 18. The chains 17 pass around sprocket wheels 19 journaled upon shafts 20, suitably mounted within the tank, and said chains may be driven from any source of power, not shown.

As was disclosed in my said co-pending application, it has heretofore been the practice to make the flights 18 of the sludge-removing conveyors of lumber which comes generally in 16-foot lengths, and it has also been customary, where the quantity of sew-

age demands it, to provide two or more division walls within the sewage tanks arranged at 16-foot intervals, and separating the tanks into 16-foot compartments, in each of which a conveyor travels.

In the present case, however, in lieu of these division walls which are expensive to construct, I have provided at suitably spaced intervals upright pillars or columns 21, 10 which, at their upper ends, support transverse beams 22, extending across the tank from side wall to side wall. The said columns or pillars also support adjacent their upper ends the longitudinally extending angles or 15 guides 23, which constitute supports for the ends of the flights of the upper runs of the conveyors, as will be readily understood from Figs. 3 and 5.

As was described in my said co-pending 20 application, it is desirable to have the flights of adjacent conveyors staggered and to have their end portions overlap transversely in order that the entire surface of the floor may be scraped. In the present instance this desirable feature is retained, although provision must be made for permitting the overlapping ends of the flights to yield as they 25 pass the upright pillars 21, as will be readily appreciated. One method of accomplishing this has been illustrated in the drawings, reference being had more particularly to Figs. 4 30 and 6. As will be clear from these figures, each end of the conveyor flights 18 is provided with a wing 30, which is pivotally connected to the flight itself at 31. The said wings 30 may have adjustable end portions 32, whereby the total length of the wing may be increased or decreased to accommodate small variations of the distance between the 35 pillars or between the pillars and the side walls. Each wing member 30 is also provided with an angular extension 33, to which is pivotally secured as at 34 one end of a rod 35, the other end of which is slidably received 40 in an aperture 36, formed in an angular bracket member 37 carried by the main body portion of the flight. A coiled spring 38 surrounds the rod 35 and has one of its ends abutting the bracket member 37, while the 45 other end abuts a washer 39, behind which is mounted a pair of lock nuts 40, threaded upon the rod 35.

The construction just described provides a 50 yielding or resilient connection between the wings and the main body of the flights 18, which permits the said wings to be pushed backwards, as they pass the pillars 21, and to then resume their normal positions in line with the flights after they have passed the said pillars. In order to relieve the impact and strain upon the parts, the bottom portions of the pillars may be provided with opposed V-shaped extensions 41, as clearly 55 shown in Figs. 4 and 6, providing inclined faces upon which the wings 30 may ride. In

order to equalize the pressures upon the flights of the conveyors adjacent the side walls 12, said walls are preferably provided with bulges or enlargements 42, opposite the pillars 21, thereby preventing the conveyors from being thrown out of alignment at these points.

It will thus be seen that the present invention provides a construction whereby it is possible to have a concrete settling tank 75 for a sewage disposal system of relatively great width as compared to those now in common use and in which the super-structure for supporting the upper runs of the sludge removing conveyors is supported upon vertical columns or pillars, while at the same time it is possible to have the entire surface of the floor subjected to the scraping action of the flights of the said conveyors, thereby completely removing the sludge which settles 80 from the sewage.

It will be understood that the lower runs 85 of the conveyors travel from right to left, as viewed in Fig. 2, and scrape the sludge into the well 43 at the inlet end of the tank, from which well the said sludge may be removed by a transverse conveyor 44, all as is disclosed in my co-pending application.

While one form of my invention has been 90 illustrated and described, it is obvious that those skilled in the art may vary the details of construction, as well as the precise arrangements of parts, without departing from the spirit of the invention, and therefore it is not wished to be limited to the above disclosure except as may be required by the 95 claims.

What I claim is:

1. In sewage disposal apparatus, a settling tank of relatively great width devoid of 105 division walls and having spaced upright columns for supporting a superstructure; and a plurality of sludge-removing conveyors in said tank having flights adapted to remove sludge from all portions of the floor of said tank which are not occupied by said 110 columns.

2. In sewage disposal apparatus, a settling tank of relatively great width devoid of 115 division walls and having spaced upright columns for supporting a superstructure; and a plurality of sludge-removing conveyors in said tank, the flights of adjacent conveyors being staggered and provided with end portions which yield to permit said flights to pass said columns.

3. In sewage disposal apparatus, a settling tank of relatively great width devoid of division walls and having spaced upright columns for supporting a superstructure; and a plurality of sludge-removing conveyors in said tank, the flights of adjacent conveyors being staggered and provided with overlapping resilient end portions which yield to permit said flights to pass said columns.

4. In sewage disposal apparatus, a settling tank of relatively great width devoid of division walls and having spaced upright columns for supporting a superstructure; a plurality of sludge-removing conveyors in said tank, the flights of adjacent conveyors being staggered and provided with pivoted end wings which overlap one another; and resilient means normally maintaining said wings in alinement with the flights, but permitting them to yield upon engagement with said columns.

5. An apparatus as recited in claim 2, in which the columns are provided with inclined surfaces, adapted to be engaged by the yielding end portions.

6. An apparatus as recited in claim 3, in which the columns are provided with diamond shaped bases adapted to be engaged by the resilient end portions.

7. In a sewage disposal apparatus, a settling tank of relatively great width devoid of division walls and having spaced upright columns for supporting a superstructure; a plurality of sludge-removing conveyors in said tank, the flights of which are provided with end portions which yield upon engagement with said columns to permit the flights to pass, the side walls of said tank being provided with projections opposite said columns to equalize the end thrust upon the flights of the conveyors adjacent to said walls.

35 In testimony whereof, I affix my signature.
GUSTAV R. RODDY.
